UNITED STATES PATENT OFFICE

RAPHAEL ARTHUR SALAMAN, OF ROYSTON, ENGLAND

CONTROL OF THEATER AND LIKE LIGHTING SYSTEM

Application filed August 10, 1929, Serial No. 385,056, and in Great Britain October 16, 1928.

This invention relates to the control of theatre and like lighting systems, and has reference to lighting systems where "dimmers" are required to be operated in such a manner as to control the period during which the dimming is effected.

In theatre lighting it is sometimes necessary to control the various lights in various ways to produce the desired scene and other effects and while it is sometimes necessary to cause the dimming operation to be completed in a few seconds it is sometimes necessary for this dimming to be effected over a much longer period.

10 The "dimming" is effected by the operation of a dimming rheostat and in accordance with the invention I utilize dimming rheostats of the kind wherein a sliding contact operates to gradually cut in and out the "dimming" resistance and the primary feature of the invention resides in the provision of a control for theatre and like lighting systems wherein is provided a rheostat actuated by hydraulic means.

20 Another feature of the invention is a control for theatre and like lighting systems wherein is provided a rheostat having a sliding contact which operates to cut in and out a light controlling resistance, actuated by hydraulic means.

One convenient embodiment of the invention is illustrated in the accompanying drawing which illustrates diagrammatically my improved control system.

rheostats 1 and 2 and their respective cylinders 7 and 8 and their pipes are provided with three-way valves 17 and 18 having branch pipes 15a and 16a leading to the mains 13 and 14 respectively. The valves 17 and 18 have setting nuts provided with indicator pointers 19 and 20 which are operative with graduated time scales 21 and 22. A pressure gauge 32 is provided on the pipe 13.

In connection with the pipe 14 is an accumulator 23 which is fed from a storage tank 24 by a pump 25. In co-operation with the accumulator 23 are contacts 26 actuated by a piston or load 27 in co-operation with a ram 28 which acts within the accumulator 23. The contacts 26 and 29 are connected with the pump 25 by electric cables 33. Between the pump 25 and the accumulator 23 is a one-way valve 29, and between the tank 24 and the pump 25 is a cock 30. Liquid is supplied to the tank 24 through a pipe 31 having a cock 32, and a float-valve 33. On the pipe 14 near the accumulator 23 is a drain-cock 34. The pump derives its electrical power through cables 35.

The rheostat 1 is connected by cables 36 to an electrical circuit 37 and to a load 38, and the load 38 by electric cables 39 to an indicator 40. The rheostat 2 is connected by cables 41 to an electrical circuit 42, and to a load 43, and the load 43 by electric cables 44 to an indicator 45.

Automatic circuit breakers 46 and 47 are fitted on the rheostats 1 and 2, which are oper-
